(57) **CLAIM**

The ornamental design for a shoe sole, as shown and described.

DESCRIPTION

FIG. 1 is a left side view, with a partial cross-section taken at the corresponding cross-sectional lines shown in FIG. 2, of a shoe sole showing my new design;

FIG. 2 is a bottom perspective view thereof;

FIG. 3 is a top plan view thereof;

FIG. 4 is a right side view thereof;

FIG. 5 is a front view thereof; and,

FIG. 6 is a rear view thereof.

The broken lines showing a shoe upper in FIG. 1, FIG. 4, FIG. 5, and FIG. 6 illustrate the environment in which the design resides, and form no part of the claim.

The broken line circle, and surface within it, in the FIG. 2 view depicts a portion of the shoe sole that forms no part of the claimed design.

The cross-section that is a part of the FIG. 1 view explains the contours of one of the three contoured elements on the shoe sole bottom. The two remaining elements on the shoe sole bottom are of similar contour, and also do not extend below the bottom surface of the shoe sole.
